DESIGN FOR A PHOTOGRAPHIC CAMERA CARRYING CASE

Joseph H. McNabb, Winnetka, Ill., assignor to The Bell & Howell Company, Chicago, Ill., a corporation of Illinois

Application August 2, 1940, Serial No. 94,131

Term of patent 14 years

To all whom it may concern:

Be it known that I, Joseph H. McNabb, a citizen of the United States, residing at Winnetka, in the county of Cook and State of Illinois, have invented a new, original, and ornamental Design for a Photographic Camera Carrying Case, of which the following is a specification, reference being had to the accompanying drawing, forming a part thereof.

In the said drawing—

Figure 1 is a perspective view of a photographic camera carrying case in closed condition and showing my new design;

I claim:

The ornamental design for a photographic camera carrying case, as shown.

JOSEPH H. McNABB.
